(57) **CLAIM**

I claim the ornamental design for a hand held horn, as shown and described.

DESCRIPTION

FIG. 1 is a front perspective view of a hand held horn showing my new design.

FIG. 2 is a side elevational view taken from the right of FIG. 1 with the opposite side being a mirror image thereof.

FIG. 3 is a rear elevational view thereof.

FIG. 4 is a front elevational view thereof.

FIG. 5 is a top plan view thereof; and,

FIG. 6 is a bottom plan view thereof.
